UNITED STATES PATENT OFFICE.

WALTER S. MOODY, OF SCHENECTADY, NEW YORK, ASSIGNOR TO THE
GENERAL ELECTRIC COMPANY, OF NEW YORK.

DESIGN FOR A TRANSFORMER-CASING.

SPECIFICATION forming part of Design No. 30,151, dated February 7, 1899.

Application filed January 10, 1899. Serial No. 701,764. Term of patent 14 years.

To all whom it may concern:

Be it known that I, WALTER S. MOODY, a citizen of the United States, residing at Schenectady, in the county of Schenectady, State of New York, have invented and produced a new and original Design for Transformer-Casings, (Case No. 1,101,) of which the following is a specification.

Referring to the drawings, Figure 1 is a perspective view of a transformer-casing, and Fig. 2 is a side elevation of the same.

As shown in the drawings, the leading feature of the design consists in the configuration of the casing.

Referring to the drawings by letter, A represents the main body of the transformer-casing, which has rounded corners B. The up-

per end of the case is enlarged at C and is provided with a curved cover D. At the lower end of the casing a base E is provided, from which extend feet F. On the sides of the casing are hooks G for convenience in handling. On the back of the casing are supporting-lugs H and I.

What I claim as new, and desire to secure by Letters Patent of the United States, is—

The design for a transformer-casing substantially as shown and described.

In witness whereof I have hereunto set my hand this 9th day of January, 1899.

WALTER S. MOODY.
